UNITED STATES PATENT OFFICE.

BENJAMIN E. ROBINSON, OF TULSA, OKLAHOMA.

SEWING-MACHINE ATTACHMENT.

1,347,406.

Specification of Letters Patent. Patented July 20, 1920.

Application filed August 3, 1918. Serial No. 248,144.

To all whom it may concern:

Be it known that I, BENJAMIN E. ROBINSON, a citizen of the United States, residing at Tulsa, in the county of Tulsa and State 5 of Oklahoma, have invented new and useful Improvements in Sewing-Machine Attachments, of which the following is a specification.

This invention relates to sewing machine 10 attachments and the object is to provide means actuated by the needle bar of a sewing machine which may be of a standard type, and which attachment is designed for holding the button in position to be sewed 15 to a garment or the like, with means for moving said button in order that each of the apertures thereof may register with the needle, permitting the thread to pass through each of the apertures in turn.

20 A further object is to provide certain novel means for retaining buttons of different sizes, and means for varying the movement of the button holding means depending upon the size of the button being 25 used.

A still further object is to provide a reciprocating element with means for actuating the latter from a needle bar of a machine of a commercial type, said means first named 30 operating a rack element actuating a rotatable element, which in turn imparts the required oscillating movement to the button holding means.

With the foregoing and other objects in 35 view the invention consists in the novel construction, combination, and arrangement of elements hereinafter described and claimed.

Figure 1 is a view in side elevation.

Fig. 2 is a view in end elevation.

40 Fig. 3 is an end elevation looking in the opposite direction.

Fig. 4 is an elevation on the side opposite to that in Fig. 1.

Fig. 5 is a top plan view.

45 Fig. 6 is a section on the line 6—6 of Fig. 5.

Fig. 7 is a section on the same line with the parts in different position.

Fig. 8 is a section on the line 8—8 of 50 Fig. 5.

Fig. 9 is a section on the line 9—9 of Fig. 5.

Fig. 10 is a diagrammatic view showing 55 various positions of the button and the member slotted radially, controlling the

movement of the button, for directing the thread through the button.

The attachment herein described includes a base plate 10 adapted to be secured in any suitable manner, this base plate having mounted thereon the operative elements of the button holding means and the mechanism for giving to the latter an oscillating movement.

Carried by the base plate 10 is a guiding member 11 and a plurality of guiding members 12 and 13 oppositely located and being spaced apart at the upper ends. Between these guiding members 11, 12, and 13, a barrel 14 is designed to reciprocate 65 when actuated by means connected with the needle bar 15 of the machine. The movement of barrel 14 is limited by stops 16 and within this barrel is mounted a plunger 17 under the control of a spring 18. 70 The underside of the barrel is provided with an aperture 19 engaged by the upturned end of a flat spring 20 which spring is thrown out of engagement when the plunger moves forward or toward the needle bar. The plunger 17 is slotted for the 75 reception of the end of lever 32 and the stem of plunger passes through element 17' fixed in the barrel and carries a head 18' at the extreme end. The first movement 80 of the lever 32 toward the left in Fig. 7 is to compress the spring 18, and when the element 20 is pressed downwardly, the barrel 14 is shot forward under the action of the spring, producing a sharp and prompt 85 movement of the button holding device by the mechanism described below, while the needle is free of the button.

Carried by the side of the barrel 14 is a flat spring 22 engaging a rack bar 24 90 which bar is movable on a plate 25 extending from the side of the barrel, the rack bar being slotted at 27 and 28, the slots extending at an acute angle with reference to the longitudinal axis of the rack bar. The 100 headed pins 29 and 30 pass through the slots and serve to guide the rack bar in its movement toward and away from a rotary member serving to give to the button and holding device the required movement for 105 placing the various apertures into position for receiving the thread.

The devices above described for actuating the rack bar are operated by means of the angle lever 32 pivoted at 33, one end 110

of this lever being slotted as shown at 34 for engagement by a pin 35 carried by a bracket or the like 36 connected with a needle bar 15 by means of the needle clamp 5 screw 37. The vertically reciprocating movement of the needle bar imparts movement to the angle lever 32 and through the mechanism specified including the barrel 14, to the rack bar and thence to the elements described below.

The base plate is upwardly deflected at point 40 and then horizontally deflected at 41, this portion last named being slotted as shown at 42 permitting member 41 to be 15 secured by the clamping screw of the pressure foot.

The button holding device is designated 45 and includes a plurality of jaws 46 and 47, the longer jaw being referred to by the 20 number last indicated. These jaws are deflected at 48 and 49 and the longer jaw is slotted as shown at 50, one edge of the slotted portion being provided with a series of teeth 54 constituting a rack, and the 25 other jaw 46 being slotted and provided with a series of teeth 54', the series of teeth last named being opposite to the series first named. A threaded spindle 57 carries a pinion 58 on its lower end, this pinion engaging each series of teeth, so that the rotation of the pinion by means of thumb nut 59 will move the jaws in opposite directions, thus providing for the holding of buttons of different sizes, the centers being in the 30 same position with reference to the needle and to the various elements of the attachment. An additional thumb nut designated 61 constitutes a lock nut. Above the shorter jaw 46 is a plate member 63, this member 35 and the aforesaid jaws being mounted within a channel member 65 having on one end thereof an extension constituting an actuating bar 66 deflected at a point intermediate of its ends as shown in drawings. The 40 free end of this bar is provided with an aperture 67 in which is mounted a flanged sleeve 68 through which passes a threaded spindle 69 engaged by thumb nut 70. The lower end of spindle 69 carries a head 71 having two flat sides and two beveled sides, the beveled portions 72 and 73 engaging the undercut walls 74 of the slot 75 in the 45 rotary disk member 76. The slot 75 extends from a point near the outer edge of the disk to a point somewhat beyond the center and permits of movement of the spindle in a direction radially of the disk, so that spindle 69 is movable toward and away from the center for adjusting the extent of 50 throw of the button holding device in order that each hole therein may register with the needle and receive the thread. Pivot 77 is

carried by an approximately U-shaped device 78 receiving the channel member 65 and permitting the reciprocating and oscillating movement of that member and of the clamping jaws carried thereby.

The disk rotates with a disk 80 having connection therewith by means of a series of pins 81 forming a device resembling a lantern wheel, the series of pins being engaged by rack bar 24, for actuating and giving the oscillating movement to the button holding means. This series of teeth in the lantern wheel is engaged by a holding 75 pawl 83 acting under the tension of a spring 84.

The operation of the device has been adequately set forth in connection with the description of the construction and will be 80 fully understood from that description.

What is claimed is:

1. In a device of the class described, a base plate, a reciprocable member mounted thereon, a rack bar movable with the reciprocable member, a rotary device, a button holding device, said rotary device being engaged by the rack bar and giving to the button holding device an oscillating movement and means for actuating the reciprocable member from the needle bar of a machine, said means including a resilient device placed under compression and then automatically released.

2. In a device of the class described, a base plate, a reciprocable member mounted thereon, means for limiting the movement of said member, a rack bar movable with the reciprocating member and having a limited independent movement with reference thereto, a reciprocating and oscillating button holding device mounted on the base plate, and a rotary member actuated by the rack bar and imparting to the button holding device reciprocating and oscillating movements.

3. In a device of the class described, a base plate, a reciprocable member mounted thereon, means for limiting the movement of said member, a rack bar movable with the reciprocating member and having a limited independent movement with reference thereto, a reciprocating and oscillating button holding device mounted on the base plate, and a rotary member actuated by the rack bar and imparting to the button holding device reciprocating and oscillating movements, said rotary member being provided with a radially extending slot, a device adjustable within said slot, and means for connecting said device last named with an element of the button holding device.

In testimony whereof I affix my signature.
BENJAMIN E. ROBINSON.
